(57) CLAIM

The ornamental design for a three sided bed guard, as shown and described.

DESCRIPTION

FIG. 1 is a front, right and top perspective view of a three sided bed guard showing my new design;

FIG. 2 is a front elevation view thereof;

FIG. 3 is a rear elevation view thereof;

FIG. 4 is a top plan view thereof, a bottom plan view thereof being omitted since it is not visible in normal use;

FIG. 5 is a left elevation view thereof; and,

FIG. 6 is a right elevation view thereof.
